UNITED STATES PATENT OFFICE.

JOHN T. LANCASTER, OF HAVERHILL, MASSACHUSETTS, ASSIGNOR TO HAMEL SHOE MACHINERY COMPANY, OF HAVERHILL, MASSACHUSETTS, A CORPORATION OF MASSACHUSETTS.

TACK-PULLER.

1,268,021.

Specification of Letters Patent. Patented May 28, 1918.

Application filed July 11, 1917. Serial No. 179,959.

To all whom it may concern:

Be it known that I, JOHN T. LANCASTER, a citizen of the United States, residing at Haverhill, county of Essex, State of Massachusetts, have invented a certain new and useful Improvement in Tack-Pullers, of which the following is a specification, reference being had therein to the accompanying drawings.

10 My invention has for its object a rotary tack puller for removing lasting tacks from boots and shoes during the process of manufacture. Lasting tacks are driven only a part of their length, and project for the remainder. 15 Rotary tack pullers, as previously constructed have tended to miss or fail to pull out some of the tacks, and to cripple or bend them. The rotary tack puller embodying my invention is much 20 more effective in this respect and also enables the workman to pull tacks much more rapidly. It is constructed so that the shoe may be fed from right to left, or from left to right, as is more convenient for the workman. 25 This enables it to be used more conveniently by a left-handed operator, and makes it possible to get out all the tacks, or to pick up tacks which have been bent over.

The invention will be fully understood from the following description taken in connection with the accompanying drawings and the novel features thereof will be pointed out and clearly defined in the claims at the close of this specification.

35 In the drawings, Figure 1 is a front elevation of a tack puller embodying my invention.

Fig. 2 is a side elevation of the tack puller shown in Fig. 1.

40 Fig. 3 is a front elevation of the two disks, said disks being separated slightly for convenience of illustration.

Fig. 4 is a side elevation of the right-hand disk shown in Fig. 3.

45 Fig. 5 is a plan view of one of the tack pulling blades.

Fig. 6 is an edge view of one of said blades.

Fig. 7 is a section on line 7—7 of Fig. 5.

50 Fig. 8 is an elevation of a modified form of tack puller embodying my invention.

Fig. 9 is a section on line 9—9 of Fig. 8.

Referring now to the drawings, at 11 is shown the shaft on which the tack puller 55 is mounted. In practice, the lasting tack

puller and a sole tack puller (not shown) are mounted at some distance from each other on the same shaft, and therefore the lasting tack puller must be of a construction capable of operating at the speed at which 60 the sole tack puller operates. In practice, I find a speed of 2000 R. P. M. produces excellent results.

The tack puller itself comprises a pair of disks 12 and 13 secured to the shaft in any 65 convenient manner, as by a spline 14. In each of the disks 12 and 13 are formed a series of cuts which are at an angle to the side faces of the two disks 12 and 13, that is, are diagonal to the periphery of the disks. 70 The cuts or slots in disk 12 are designated 15 and the slots in disk 13 are designated 16. In practice I make the slots in disk 12 at an angle of about 8° with the left-hand face and the slots in disk 13 at the same angle 75 with the right-hand face of the said disk, and locate the slots so that the ends of the slots register with each other as is shown in Fig. 3. The pairs of slots 15 and 16 therefore converge, or form an angle, one with the other. In the form shown in the drawings 80 the ends of the slots emerge on the surface of the disk forming triangular cutaway places as shown in Fig. 4.

In each of the slots is located a tack pulling blade 17. These blades, see Figs. 5 to 7, consist of flat plates, each of which is of the thickness of the slots 15 and 16. The edge of the blade from the point *a* to the point *b* is practically the arc of the circumference 85 of a circle formed about the axis of rotation as the center. The part of the edge from *b* to *c* is of any convenient slope so that a square end will not be formed which would strike the shoe and damage it. The edge 90 95 of the blade is at substantially a right angle to the plane of the blade as will be seen from Fig. 7. This edge, which may be referred to conveniently as an inturned edge or flange, is formed by milling or cutting out a 100 groove *d*, of the proper depth, adjacent the working edge of the blade. The inturned edge of the blade is preferably cut away at intervals to form notches or teeth *e*, see Fig. 6. The blades are of such a length as to 105 leave a space *f* between the heels *a* of one pair of blades, and the toes *c* of the adjacent pair of blades. This space affords the opportunity for the projecting tack to be properly presented to the tack pulling blades, as the 110

shoe is moved laterally across the periphery of the tack puller, by the operator. The proximate ends *a a* of a pair of converging blades do not touch each other; on the contrary a space is left between them which prevents tacks catching there, and permits the device to clear itself.

The blades are secured in the disks in any convenient manner, as for instance by bolts 10 19 and nuts 20, passing through the two disks and the adjacent pair of blades, from side to side.

In Figs. 8 and 9, I have shown a modified form of my improved tack puller, which 15 differs from the form already described chiefly in respect to the shape of the in-turned flange on the tack pulling blades.

In the form shown in the modification the blades converge and meet at *g*, but no 20 notches or teeth are cut in the in-turned flange 21 of the blades 22, but the in-turned flange is continuous throughout its entire length, except at the point where the ends of the blades come together. At this point 25 the flange is cut away as shown at *h* so that the tack puller will clear itself of tacks which have been extracted, and which would otherwise tend to catch in the V-shaped space formed by the junction of the two adjacent tack pulling blades.

While for ordinary work I prefer to employ the form of blade shown in Figs. 5 to 7 inclusive, since the notches tend to make the blades more effective, I find a tack puller 35 provided with blades of the form shown in the modification is practically as satisfactory on general work, and particularly when run at a relatively high rate of speed.

As the shoe is fed across the face of the 40 tack puller, the tack enters the space between the toe of one blade and the heel of another. The shoe rests against the smooth edge of the blades and cannot be cut or injured by the blades. The shoe is fed or 45 pushed along by contact with the portion of the blade between the points *c* and *b*, which portion has no in-turned flange. At this point, the flange passes under the head of a tack or the stem of the tack, contacts 50 with one of the teeth and further motion of the tack puller extracts the tack from the shoe. The successive teeth and the successive blades catch any tack which is not extracted by its first contact with the device. 55 If the tack becomes crippled or the side of the head is broken away so that the in-turned flange on the tack pulling blades on the side of the tack puller at which the tack enters, fail to remove the tack, then the tack is 60 caught and extracted by the blades on the opposite side; that is, assuming that the shoe is being fed from the right, if the blades on the disk 12 do not remove the tack or bend it over toward the left, the blades 65 on the disk 13 are almost certain to catch

and remove it. The device is easy to feed because the blow which one tack pulling blade strikes the tack pushes the shoe along and causes the next tack to enter one of the spaces between succeeding blades.

I find in practice that tack pullers made in accordance with the drawings herein are exceedingly effective in removing tacks and that they practically never fail to remove a tack which is within reach, and that the 75 tacks are not crippled or bent over and thus missed, as is frequently the case with tack pullers as heretofore constructed.

What I claim is:

1. The improved rotary tack puller comprising a disk and a tack extracting blade, the edge of which is concentric with the axis of rotation of the disk, said blade being set diagonally of the periphery of the disk and having a flange along the side of the peripheral edge.

2. The improved rotary tack puller comprising a disk and a tack extracting blade, the edge of which is concentric with the axis of rotation of the disk, said blade being set diagonally of the periphery of the disk and having a notched flange along the side of the peripheral edge.

3. The improved tack puller comprising a rotary member provided with a blade arranged diagonally of the periphery thereof, and having an in-turned notched flange along its effective edge.

4. The improved tack puller comprising a rotary cylindrical member provided with a series of blades arranged diagonally of the periphery thereof, and said blades having an in-turned notched flange along their effective edges.

5. The improved tack puller comprising a rotary cylindrical member provided with slots diagonally of the periphery thereof, and blades in said slots, each of said blades having an in-turned flange along its effective edge.

6. The improved tack puller comprising two adjacent disks arranged to rotate on the same axis and each provided with a series of blades arranged diagonally of the periphery thereof, said blades having in-turned flanges along their effective edges.

7. The improved tack puller comprising two adjacent disks arranged to rotate on the same axis and each provided with a series of blades arranged diagonally of the periphery of the respective disks, and at an angle to each other and, said blades having in-turned flanges along their effective edges.

8. The improved tack puller comprising two adjacent disks arranged to rotate on the same axis and each provided with a series of blades arranged in pairs, one on each disk, diagonally of the peripheries of the respective disks, and at an angle to each other, the proximate ends of the two blades

- of each pair of disks being at a distance from each other to permit the passage of a tack, and said blades having inturned flanges along their effective edges.
- 5 9. The improved tack puller comprising a rotary member provided with a series of flat blades arranged diagonally of the periphery thereof, and having an edge concentric with the axis, said edge being formed into a projecting flange.
10. The improved tack puller comprising a rotary cylindrical member provided with a series of blades arranged diagonally of the periphery thereof and having inturned flanges along their effective edges, said 15 flanges being formed on the side of the blade and the edge of the blade being smooth to form a suitable rest for the shoe.

In testimony whereof I affix my signature.

JOHN T. LANCASTER.
